UNITED STATES PATENT OFFICE.

WALTER Y. ROBB, OF WHITINSVILLE, MASSACHUSETTS, ASSIGNOR TO CROMPTON & KNOWLES LOOM WORKS, OF WORCESTER, MASSACHUSETTS, A CORPORATION OF MASSACHUSETTS.

THREAD CUTTER FOR LOOMS.

Application filed April 18, 1927. Serial No. 184,652.

This invention relates to improvements in thread cutters for looms and more particularly to improved means for operating the same.

5 In co-pending application Ser. No. 127,695 there is shown a thread cutter mounted on a shuttle feeler of the type ordinarily employed in multi-color weft replenishing mechanisms such as shown in Patent No. 1,030,748. The 10 cutter shown in said application comprises a jaw pivoted to the shuttle feeler and connected to an operating rod the upper end of which is pivotally connected to a fixed stud. In said application the stud is held by a 15 bracket secured to the loom frame and it has been found in adapting this form of cutter to various styles of magazines that considerable variation exists in the forms of loom frames used. Up to the present time it has been necessary to provide a different kind of bracket 20 for each loom frame to which the cutter is applied and it has been found necessary to make a large number of brackets. It is an important object of my present invention to provide 25 a holder for the upper end of the cutter operating rod to be mounted on a part of the magazine independently of the loom frame so that one holder will suffice for a number of different loom constructions.

30 It is also true that considerable variation exists in the width of multi-color weft replenishing mechanisms, some of these devices being designed for looms of two colors while others are of sufficient width to accommodate 35 six different kinds of bobbins. It is a further object of my present invention to provide a holder for the cutter operating rod which shall be adjustable on a portion of the weft replenishing mechanism so that the same 40 holder may be employed for magazines of different widths. In this connection it may also be stated that magazines for four colors are not always of the same width, as those made for cotton blankets are ordinarily wider than 45 those made for gingham looms due to the increased diameter of the bobbin rendered necessary by the coarseness of the filling used in weaving blankets.

50 A still further object of my invention is to provide a common mounting for the cutter and the holder for the cutter operating rod to the end that the whole device may be assembled and adjusted independently of the weft replenishing mechanism or of the loom and

then fitted in place, the relation between the 55 cutter and its operative rod remaining the same when on the loom as when originally assembled.

With these and other objects in view which will appear as the description proceeds, my 60 invention resides in the combination and arrangement of parts hereinafter described and set forth in the claims.

65 In the accompanying drawings wherein one form of my invention is shown,

Fig. 1 is a side elevation of the lower part of a multi-color weft replenishing mechanism viewed from the center of the loom and having my invention applied thereto, parts of the lay being shown in section,

70 Fig. 2 is a vertical section on line 2—2 of Fig. 1, and

Fig. 3 is an enlarged horizontal section on line 3—3 of Fig. 2.

Referring to the drawings the loom frame 75 10 has mounted thereon a foot 11 of a multi-color weft replenishing mechanism of the type set forth in the aforesaid Patent No. 1,030,748. Said mechanism accommodates a plurality of vertical stacks of bobbins which 80 are discharged by a transfeerer T into the shuttle S held on the lay L. Multi-color weft replenishing mechanisms use a shuttle feeler of the type set forth in patent to Ryon No. 1,022,108 and also a so-called color slide, the 85 office of which is to select a bobbin of the color corresponding to the depleted shuttle. Both the shuttle feeler and the color slide operating lever are ordinarily mounted on the same casting and I have shown a similar construction 90 herein. The frame 12 has bolted thereto a carrier 13 from the lower end of which project two spaced parallel studs 14 and 15, respectively. Said studs are both secured to the carrier as indicated and the rear stud 15 has 95 mounted thereon lever 16 the horizontal arm 17 of which is connected to the shuttle box mechanism and the vertical arm of which is connected to the aforesaid color slide not shown herein but set forth in the Ryon Patent 100 No. 1,030,748. The forward stud 14 has mounted thereon a shuttle feeler holder 18 having pivotal connection with the lower end of an upright rod 19 and giving support to a 105 pressed metal shuttle feeler 20 the lower end of which is curved as at 21 to cooperate either with the front wall of misplaced shuttles or the curved upper part of the box back 22 as

the lay advances. Normally the shuttle feeler 20 is in the raised position shown in Fig. 1, but at the time of transfer mechanisms not shown herein but well understood and set forth in the aforesaid Patent No. 1,022,108 operate to lower the rod 19, thus placing the curved portion 21 of the shuttle feeler in the path of the advancing lay and shuttle. If the shuttle be misplaced it will engage the shuttle feeler and restore the latter to its raised position, thus lifting rod 19 to prevent transfer. The matter thus far described is commonly employed in practically all multi-color weft replenishing mechanisms.

15 The color mechanism, as previously stated, is substantially the same as that set forth in the Chevrette application and comprises a cutter jaw 30 pivoted as at 31 to the shuttle feeler and having a rearwardly extending cutter blade 32 indicated in dotted lines in Fig. 1. A thread clamp 33 is secured to the shuttle feeler and is held by its own resilience against that face of the cutter blade 32 adjacent the fabric. The cutter jaw 30 has an 20 upwardly extending arm 34 which has pivotal attachment with an adjustable cutter operating rod 35 provided with a turnbuckle 36 by means of which the length of said rod may be adjusted. The matter thus far described forms no part of my invention and 25 may be as set forth in said patents and application.

In carrying my invention into effect I extend the rear stud 15 inwardly toward the 30 cloth and secure thereto a rod holder 50 having a hub 51 thereto into which the extending rod 15 projects, set screw 52 securing the holder to the stud 15 in adjusted angular position. The upper end of said holder is 35 provided with an elongated slot 53 which may extend radially from the stud 15. A stud 54 is held adjustable in said slot 53 as indicated in Fig. 3, said stud having an enlarged head 55 which furnishes a bearing for the upper rod head 56 formed on the rod 35.

In operation the parts are normally in position shown in Fig. 1 and at the time of transfer the rod 19 will be depressed, as previously stated, this action being accompanied by an 40 opening of the cutter jaw 30 due to the fact that the upper end of the rod 35 is fixed. When the shuttle feeler is raised as the lay reaches its front position the jaw 30 will be restored to normal position, thus cutting the 45 thread and placing the latter between the clamp 33 and the cutter blade 32.

It will be readily apparent that by adjusting the position of the holder 50 with respect to stud 15 the upper end of the rod holder 50 can be given the proper position irrespective of the width of the magazine or the distance between the center about which the cutter jaw 30 moves and the location of stud 15. The slot 53 also provides means for giving a 55 greater or less opening to the cutter. It is ap-

parent that the stud 54 can be given a multiplicity of adjusted positions with respect to the stud 14, the relation between the centers of the studs 14 and 54 determining in large measure the manner in which the cutter operates. 70

In the foregoing it will be seen that I have provided a simple holder for the upper end of the cutter operating rod, said holder being adjustable angularly and longitudinally 75 along stud 15 and stud 54 being adjustable in the slot 53, the turnbuckle 36 providing further means for adjusting the rod 35. By means of the construction set forth the assembled structure is mounted on the carrier 80 13 and is capable of a wide range of adjustment such as will adapt the same to use in a variety of multi-color weft replenishing mechanisms.

Having thus described my invention it will 85 be seen that changes and modifications may be made therein by those skilled in the art without departing from the spirit and scope of the invention and I do not wish to be limited to the details herein disclosed, but 90 what I claim is:

1. In a thread cutting and clamping device for weft replenishing mechanisms, a carrier mounted on the weft replenishing mechanism, a shuttle feeler pivotally mounted with respect to the carrier, a thread cutting unit mounted on the shuttle feeler, a rod holder 95 adjustably mounted on the carrier to assume a plurality of angular positions relatively to the carrier, and an operating rod interposed between a portion of the cutting unit and the holder, said rod being effective to operate the unit with respect to the shuttle feeler as the latter moves pivotally with respect to the carrier. 100

2. In a thread cutter and clamp for looms, a carrier secured to the weft replenishing mechanism, a stud extending from said carrier, a shuttle feeler pivotally mounted on the stud, a thread cutting unit mounted on 110 the shuttle feeler, pivotal movement with respect thereto, a rod holder on the carrier fixed with respect to the stud but capable of assuming a plurality of adjusted angular positions with respect to said stud, and a rod 115 connecting the holder and the thread cutting unit to operate the latter as the shuttle feeler moves about the stud as a pivot.

3. In a thread cutting device for weft replenishing mechanisms, a pair of separated 120 studs fixed with respect to the replenishing mechanism, a shuttle feeler pivotally mounted on one of the studs, a thread cutter mounted on the shuttle feeler, a rod holder held in angularly adjusted position on the other stud 125 and having a slot therein, a stud adjustable on the holder and extending through the slot, and a cutter operating rod having one end attached to the last named stud holder and having the other end attached to the thread 130

cutter, said cutter being operated by the rod when the shuttle feeler moves about the stud on which it is mounted as a pivot.

4. In a thread cutter and clamping unit for looms, a carrier secured to the weft replenishing mechanism, means rigid with the carrier defining a slot, a stud located in the slot and adjustable longitudinally along said slot, a shuttle feeler pivotally mounted with respect to the carrier, a thread cutting and clamping

unit mounted on the shuttle feeler for pivotal movement with respect thereto and a rigid connection one end of which is pivotally connected to the cutting and clamping unit and the other end of which is connected to said stud. ¹⁵

In testimony whereof I have hereunto affixed my signature.

WALTER Y. ROBB.
